UNITED STATES PATENT OFFICE.

CHARLES SCHACHT, OF MARINE, ILLINOIS.

FLOUR-BOLT.

SPECIFICATION forming part of Letters Patent No. 251,954, dated January 3, 1882.

Application filed July 30, 1881. (No model.)

To all whom it may concern:

Be it known that I, CHARLES SCHACHT, of Marine, in the county of Madison and State of Illinois, have invented a certain new and useful Improvement in Flour-Bolts, reference being had to the accompanying drawings, forming a part hereof.

My invention relates to revolving bolts, and its object is to provide means for keeping the bolting-cloth free from all obstructing material and to prevent the flour from caking upon the cloth.

It is a well-known fact that the friction produced with the reduction of grain between the burrs brings the flour to a temperature at which it will readily cake and will have a tendency to clog the meshes of the bolting-cloth, and this tendency of caking is increased with the higher grades of flour.

My invention consists of looped fringes of cord, cloth strips, or leather straps pending from rods or stretched ropes or cables that are placed parallel with the bolting-reel into the bolt-chest, and in such relation to said bolting-reel that these fringes will drag upon and against the bolt, and that as the latter revolves these fringes will sweep over and strike against the bolting-cloth, thereby preventing the flour from caking against and clogging the bolting-cloth, as more fully hereinafter described.

In the accompanying drawings, Figure 1 represents a cross-section of the bolting-chest and flour-bolt having my improvement. Fig. 2 is a perspective view of the same with one side and the top of the bolting-chest removed. Fig. 3 is an elevation of one arrangement of the looped fringes of cord or other flexible strips as attached to their suspending rod or cable, and Fig. 4 is an elevation of another arrangement of the same.

The same letters designate the same or corresponding parts in all the figures.

A denotes the bolting-chest, and B the hexagon or octagon bolting-reel, all of which may be constructed and arranged in any usual manner.

C D are two metal or wooden rods or cables, one along the rear and the other one above the bolt. These rods or cables are to extend the entire length of the bolting-chest, and are se-

cured to the end walls by any well-known means, or may be made to project through the end boards, so as to be held rigidly in position. To each of these rods is secured a series of loops, a and b, made of cord, of strips of cloth, or of straps of leather, or of any other material that is flexible and is suitable in other respects. These loops may be single, or may be two or more, one inside the other, and every one or every set may be attached to the rod or cable so as to adjoin the next one or the next set, as shown in Fig. 3; or these loops may be suspended in a manner to overlap each other, as shown in Fig. 4, and only one rod or cable with flexible loops may be used instead of two, as shown in Figs. 1 and 2, all of which will depend upon the kind and nature of the flour to be bolted. For the purpose of adjusting the loops as to their length and their extent of contact with the bolting-reel, I can provide the rods C and D, each on the end that projects through the end wall of the bolting-chest, with a ratchet-wheel, so that it can be rotated to wind up a portion of or the entire loops, and hold them in the desired position by locking the ratchet-wheel with a pawl pivoted to the bolting-chest; or I can arrange the rods or cables so that they will move in slots in the end walls of the bolting-chest, so that they may be moved and adjusted vertically. With the rotation of the bolt-reel the flexible loops will sweep over the bolting-cloth, and by passing each corner of the reel these loops will strike a light blow upon the bolting-cloth, that is sufficient to knock off any caking flour or other obstructions, and thus will keep the meshes clean and open; or with the new process of reduction the irregularly-shaped middlings, which are apt to stick in the meshes, will be repulsed into the flour-bolt by the sweeping and striking action of the loops.

These flexible loops have the advantage over brushes or flexible flaps that they will not obstruct the circulation of the atmosphere through the bolts, which is of great importance for cooling the flour, as otherwise the caking of the flour will take place more readily; and another advantage is that these loops will not damage the bolting-cloth, as is the experience with the use of brushes for a like purpose.

Another advantage secured by the use of the loops herein described over those bolts where a flap or flaps is or are used is that the loops only strike against a small portion of the bolt-cloth at one time, but yet touch it over all parts as the reel turns, and thereby clean the entire surface thoroughly. The circulation of air brought about by the rotation of the reel is not obstructed by the loops, as it would be to a certain extent by a flap. A piece of cloth can be better cleaned from dust adhering thereto by striking it with a stick or a rope at different places than would be the case were one cloth to be struck with another over its whole surface at once, or even if such cloth were struck by a board over its entire surface at one time.

By the means of the herein-described devices a higher grade of flour is obtained, the

bolting-cloth will be more durable, and the bolts will perform more work.

What I claim as my invention is—

The combination, with a reel-bolt, of one or more rods suspended within the bolting-chest and a series of flexible loops suspended from said rod or rods, to adapt them on the rotation of the reel-bolt to drag upon or against the bolting-cloth, substantially as and for the purpose described.

In testimony whereof I have signed this specification, in the presence of two witnesses, this 22d day of July, 1881.

CHARLES SCHACHT.
